US00D479097S

(12) **United States Design Patent** (10) Patent No.: **US D479,097 S**
 Willis (45) Date of Patent: ** *Sep. 2, 2003

(54) **BOWL**(75) Inventor: **Donald M. Willis**, Chino Hills, CA (US)(73) Assignee: **Pactiv Corporation**, Lake Forest, IL (US)

(*) Notice: This patent is subject to a terminal disclaimer.

(**) Term: **14 Years**(21) Appl. No.: **29/171,571**(22) Filed: **Nov. 25, 2002****Related U.S. Application Data**

(63) Continuation-in-part of application No. 29/170,596, filed on Nov. 8, 2002, and a continuation-in-part of application No. 29/170,691, filed on Nov. 13, 2002, and a continuation-in-part of application No. 29/170,597, filed on Nov. 8, 2002.

(51) LOC (7) Cl. .... **07-01**(52) U.S. Cl. .... **D7/565**; D7/584; D9/428; D9/429(58) **Field of Search** .... D7/565, 540, 542, D7/560, 562, 584, 601, 602, 533.6, 545, 629; 220/575, 574, 4.27, 23.87; 206/457; D9/428-429; D30/120(56) **References Cited**

(57) **CLAIM**

The ornamental design for a bowl, as shown.

DESCRIPTION

FIG. 1 is a perspective view of a bowl.

FIG. 2 is a top view of a bowl.

FIG. 3 is a bottom view of a bowl; and,

FIG. 4 is a side view of a bowl.

1 Claim, 3 Drawing Sheets# US D479,097 S
